UNITED STATES PATENT OFFICE.

GALEN A. HAIGHT, OF DETROIT, MICHIGAN.

TOY.

Application filed January 4, 1923. Serial No. 610,724.

To all whom it may concern:

Be it known that I, GALEN A. HAIGHT, a citizen of the United States, residing at Detroit, in the county of Wayne and State of Michigan, have invented a new and useful Improvement in a Toy, of which the following is a specification.

My invention relates to a new and useful improvement in a toy adapted for use with kites and the like for conveying messages and parachutes to the kite upon the kite string the toy serving as a trolley for conveying the articles to the kite where they will be automatically released from the conveyor and has for its object the provision of such a toy which will be simple in structure, economical of manufacture and highly efficient in use.

Another object of the invention is the provision of a toy of the class described having a keeper mounted slideably on the main body portion of the device, the retaining members for said keeper being struck from the main body.

Another object of the invention is the provision of a toy of the class described having a slideable keeper mounted on the main body portion and so formed as to prevent its undue removal from the said body portion.

Another object of the invention is the provision of a toy of the class described having wheels mounted thereon, the bearings for the shaft upon which said wheels are mounted being formed integral with the main body portion.

Other objects will appear hereinafter.

The invention consists in the combinations and arrangements of parts hereinafter described and claimed.

The invention will be best understood from a reference to the accompanying drawings which form a part of this specification and in which,

Fig. 1 is a side elevational view of the invention mounted on a kite string,

Fig. 2 is a central longitudinal sectional view of the invention showing parts in section and parts in elevation,

Fig. 3 is a top plan view of the invention,

and

Fig. 4 is a sectional view taken on substantially line 4-4 of Fig. 2.

The preferred form of structure comprises a main body portion 9 punched out of which are tongues 10, 11 and 12, each of which is provided with an opening in which is ex-

tending for slideable movement a rod 13, one end of which is doubled upon itself to form a U-shaped portion, said end 16 being sharpened and the tongues 10 and 11 being each provided with an additional opening for the reception of the doubled over portion of the rod. The rod 13 is provided with a stop at 14 and 15 to prevent the removal of the rod from operative position, said stops being formed by a crimping of the rod. These stops are so positioned that when the rod is moved to inoperative position the sharpened end will still be projected through the tongue 11. Projecting outwardly from the main body along the edges thereof are flanges 17 and 18 projecting outwardly from which are tongues 19, 19', 20 and 20' which are provided with openings adapted for the reception of a shaft on which is mounted a pulley wheel, one wheel 21 being at one end of the body and another wheel 22 being at the opposite end of the body. One end of the body is provided with a tongue 23 which is turned backwardly upon the main body toward the wheel 22 the extreme end 23' thereof being curled so that a suitable guide for a cord or string upon which the pulley rides is formed. The opposite end of the main body is likewise provided with a guide formed from the portions 24 and 24'. Fastened to the kite string 26, adjacent the kite 27 is an abutment member 25 which may be formed from card board, metal or other suitable material.

The device is used as a toy for conveying a parachute 28 up a kite string and then releasing it to fall to earth, the strings of the parachute being provided with sufficient weight to bring the parachute downwardly in upright position so that it will fill with air, as will be readily understood. The parachute is provided with a ring or other suitable means for engaging the leg of the U-shaped portion of the rod. This rod is then moved so that the end 16 is projected through an opening formed for its reception in the tongue 10. The device is mounted on the string 26 of the kite, the wheels provided with flanges to form a channel for the string to ride in. The inturned ends of the main body portion serve as guides to prevent the displacement of the string from the channels of the wheels. The wind will then under ordinary conditions serve to cause the device to travel upwardly on the string.

When the forward end of the rod 18 strikes the abutment 25 the rod will be moved backwardly so as to release the object carried on the doubled over portion of the rod 18.

5 In use the device may also be used to carry small pieces of paper, and the like, the sharpened end of the rod being thrust through the paper. The method of release is then the same, the tongue 11 serving as a 10 back to allow the removal of the paper from the rod when moved to inoperative or releasing position.

While I have illustrated and described the preferred form of structure I do not 15 wish to limit myself to the precise form of structure shown but desire to avail myself of such variations and modifications as come within the scope of the appended claims.

Having thus described my invention 20 what I claim as new and desire to secure by Letters Patent is:

1. A toy of the class described comprising a main body portion; flanges mounted on and integral with said body portion; 25 tongues punched from said body portion and integral therewith, said tongues being provided with openings formed therein; a keeper slidably mounted on said body and projected through said tongues one end of 30 said keeper being formed U-shaped, the free end thereof being sharpened and projected through a plurality of said tongues; means

mounted on said keeper for preventing its removal from said tongues; standards carried by and integral with said flanges 35 wheels mounted on said standards and provided with channels for the reception of a cord; and guide members integral with said body portion for preventing the removal of said cord from said channels. 40

2. A toy of the class described comprising a main body portion, flanges mounted thereon and integral therewith; tongues punched from said main body portion and integral therewith, said tongues being provided with openings formed therein; rotatable members mounted on said body portion; a keeper projected through said openings; and guides at opposite ends of said main body portion, comprising an overturned portion thereof, the end thereof being angularly turned. 45 50

3. In a toy of the class described, a main body portion; rotatable members mounted thereon; and guide members positioned adjacent each of said rotatable members comprising a doubled-over portion of said main body portion and having the ends thereof angularly turned downwardly toward said main body portion. 55 60

In testimony whereof I have signed the foregoing specification at Detroit, in the county of Wayne and State of Michigan.

GALEN A. HAIGHT.
